Specification for Design.

Patented Jan. 17, 1922.

Application filed September 27, 1921. Serial No. 503,625. Term of patent 7 years.

To all whom it may concern:

Be it known that I, DUDLEY FREEMAN, a citizen of the United States, residing at Roxbury, in the county of Suffolk and Commonwealth of Massachusetts, have invented a new, original, and ornamental Design for a Shoe Heel, of which the following is a specification, reference being had to the ac-

companying drawing, forming a part thereof.

The figure of the drawing is a plan view of a shoe heel incorporating my new design.

I claim:

The ornamental design for a shoe heel as shown.

DUDLEY FREEMAN.
